JACOB J. SPRUNGER, OF FORT WAYNE, INDIANA

WEDGE FOR TOOL HANDLES

Application filed November 26, 1928. Serial No. 321,783.

This invention relates to improvements in wedges for tool handles especially adapted for securing a handle in the socket of a hammer head or other tool into which a handle is driven into a socket made therein for its reception. The object of the invention is to provide a wedge of increased effectiveness in expanding the end of the handle in the socket of the tool secured thereon. Another object is to so construct the wedge that it may be more readily driven into the handle with a decreased tendency of splitting the handle as compared with the ordinary wedge, and another object is to so form the wedge as to lessen the tendency to become loose and work out of position as is frequently experienced where wedges of the ordinary construction are employed. A further object is to so shape the wedge as to increase the extent of the surface thereof that bears against the surrounding handle substance into which it is driven.

These objects are accomplished by the construction illustrated in the accompanying drawings, in which:—

Fig. 1 is a perspective view of a hammer head disposed upon a handle secured by a wedge embodying the invention;

Fig. 2 is a side elevation of a wedge embodying the invention, a portion thereof being cut away;

Fig. 3 is a top view projected from Fig. 2; and

Fig. 4 is a perspective view of the wedge.

The invention consists of a wedge 1, one end of which presents a straight sharpened edge 2. The front and back surfaces 3 of the wedge are divergent and extend in corresponding planes from the sharp edge 2 to the top of the wedge. The sides 4 of the wedge extend divergently from the sharpened end to the top of the wedge, and the surfaces thereof are concave, and the corners 5 and 6 are sharp, and each of said corners extends divergently with respect to the other corners. In the front and back of the wedge is made a cavity 7 that extends from the top of the wedge to a point spaced from the sharp edge 2 at the bottom end, the cavity being so shaped as to taper from the corresponding edges 5 at the top of the wedge to a point 8

located midway between said edges adjacent the sharp edge 2, there being formed in the front and back of the wedge a corresponding pair of surfaces 9 and 10 that are divergent laterally with respect to each other, the surfaces 9 and 10 on the front of the wedge being also divergent from the point 8 to the top of the wedge with respect to the corresponding surfaces 9 and 10 on the back of the wedge. In this manner the wedge is so formed that all of the surfaces exposed by its front and back and its sides are divergent with respect to each other, and the extent of the area of the wedge that contacts with the surrounding substance when the wedge is driven into the handle is augmented.

In utilizing the invention the handle 11 is driven into the head 12 of the tool and the wedge is applied in the usual manner by driving it into the exposed end of the handle so that the inserted end of the handle is expanded tightly in the head and thus firmly secured therein. The divergence of the concave sides 4 being of less acuteness than the sides of the wedge at the corners 5 and 6, and the divergence of the surfaces 9 and 10 in the front and back of the wedge being similarly of less acuteness than the wedge at the corresponding corners 5 and 6, permits the wedge to enter the handle more readily when driven thereinto, and with less tendency of splitting the handle, than the ordinary wedge, the contacting surfaces of which are divergent with the same acuteness at its corners. A further advantage of the wedge in which the present invention is embodied is that the wedge is more firmly held in place because of the acuteness of its concave sides and the front and back surfaces 9 and 10.

While the sides of the wedge are shown as concave, and the cavities made in the front and back are shown so as to present the divergent planes 9 and 10, it is not the intention that the invention shall be confined to the particular form illustrated, as the chasms made in the sides of the wedge, and in the front and back thereof by making the sides concave and forming cavities in the front and back of the wedge, may be differently shaped without loss of the characteristics of

the wedge or departure from the invention. As the chasms in the vertically inclined faces of the wedge are disposed longitudinally, the wedge is held as it is being driven into the handle, to a course in line with its longitudinal center which enables the operator to drive the wedge accurately into place. As the substance of the handle extends into the chasms, the wedge is guided thereby during the driving operation, and deflection of the wedge is prevented.

What I claim is:—

A wedge having a sharp edge at one end, the front, back and sides of said wedge extending divergently from said sharp edge and each having formed therein a longitudinally disposed chasm, the chasms in the front and back being spaced from said sharp edge and extending laterally at their upper ends to the corresponding sides of the wedge, and the chasms in the sides extending throughout the entire length of the wedge.

In testimony whereof I affix my signature.
JACOB J. SPRUNGER.
